Des. 198,877
Patented Aug. 11, 1964

198,877

SOLUTION STORAGE AND REPLENISHMENT MACHINE

Ralph M. Vigna, Rochester, N.Y., assignor to Eastman
Kodak Company, Rochester, N.Y., a corporation of
New Jersey

Filed Aug. 6, 1963, Ser. No. 76,133

Term of patent 14 years

(Cl. D61—1)

FIG. 1 is a front perspective view of a solution storage and replenishment machine showing my new design; and FIG. 2 is a rear perspective view thereof.

I claim:

The ornamental design for a solution storage and replenishment machine, as shown.
